(57) **CLAIM**

The ornamental design for a simulative flower attachment for a shower, as shown and described.

DESCRIPTION

FIG. 1 is a top plan view of the simulative flower attachment for a shower in accordance with our invention; the bottom plan view being a mirror image thereof;

FIG. 2 is a first side elevation view of FIG. 1; the second side elevational view being a mirror image thereof;

FIG. 3 is front elevation view of FIG. 1; the back elevational view being a mirror image thereof; and,

FIG. 4 is a perspective view of the simulative flower attachment for a shower of FIG. 1; the broken lines forming no part of the claimed invention.
